UNITED STATES PATENT OFFICE

95,880

DESIGN FOR A LADY'S SUIT

Sidney Vlock, New York, N. Y.

Application February 21, 1935, Serial No. 55,553

Term of patent 3½ years

To all whom it may concern:

Be it known that I, Sidney Vlock, a citizen of the United States of America, residing in Manhattan, county of New York, and State of New York, have invented a new, original, and ornamental Design for a Lady's Suit, of which the following is a specification, reference being had to the accompanying drawing, forming part thereof, wherein,

I claim:

The ornamental design for a lady's suit, substantially as shown.

SIDNEY VLOCK.
